(57) **CLAIM**

I claim the ornamental design for a bottle warmer, as shown and described.

DESCRIPTION

FIG. 1 is a perspective view of a bottle warmer, showing my new design;

FIG. 2 is a front view thereof;

FIG. 3 is a back view thereof;

FIG. 4 is a left side view thereof;

FIG. 5 is a right side view thereof;

FIG. 6 is a top view thereof, with the bottle removed; and, FIG. 7 is a perspective view thereof, with the bottle removed.

The dashed lines are included for illustrating environmental structure and form no part of the claimed design.

1 Claim, 4 Drawing Sheets*FIG. 1*

FIG. 2**FIG. 3**

FIG. 4**FIG. 5**

FIG. 6

FIG. 7
